LITTER RETRIEVER

Peter A. Dorzan, 1 Muir Place, Vauxhall, N.J. 07088

Filed May 20, 1971, Ser. No. 145,593

Term of patent 14 years

Int. Cl. D30—99; D8—05

U.S. Cl. D30—99

FIG. 1 is a perspective view of the litter retriever, showing my new design;

FIG. 2 is a front elevation view thereof, which is a mirror image of a rear elevation thereof;

FIG. 3 is an elevation view of the left side thereof;

FIG. 4 is an elevation view of the right side thereof;

FIG. 5 is a top plan view;

FIG. 6 is a bottom plan view.

I claim:

The ornamental design for a litter retriever, substantially as shown and described.
